Harry J. Carlin, Brooklyn, N. Y.

Application April 25, 1936, Serial No. 62,308

Term of patent 7 years

To all whom it may concern:

Be it known that I, Harry J. Carlin, a citizen of the United States of America, and a resident of Brooklyn, county of Kings, in the State of New York, have invented a new, original, and ornamental Design for a Handbag, of which the following is a specification, reference being had to the accompanying drawing, forming a part thereof.

Fig. 1 is a front view of a handbag showing my new design; and

The dominant features of my design reside in the arrangement of two short loops secured to one end of the bag, and a single, longer loop passing through the two shorter loops and secured to the opposite end of the bag as shown.

I claim:

The ornamental design for a handbag as shown and described.

HARRY J. CARLIN.
